United States Patent Office.

GEORGE LANE, OF HAMILTON, OHIO.

Letters Patent No. 77,055, dated April 21, 1868.

IMPROVED BOOT-HEEL.

The Schedule referred to in these Letters Patent and making part of the same.

TO ALL WHOM IT MAY CONCERN:

Be it known that I, GEORGE LANE, of Hamilton, in the county of Butler, and State of Ohio, have invented a new and useful Improvement in Boot and Shoe-Heels; and I do hereby declare the following to be a full, clear, and exact description thereof, which will enable others skilled in the art to make and use the same, reference being had to the accompanying drawings forming part of this specification, in which—

Figure 1 is a perspective view of my improved boot and shoe-heel, and

Figure 2 a perspective view with the flange or band removed.

Similar letters of reference indicate corresponding parts.

This invention relates to an improved boot and shoe-heel, and it consists in providing the ordinary boot or shoe-heel with a supplementary bottom, composed of India rubber, or other equivalent elastic material, placed in a metallic case, whose flange fits over the heel of the boot or shoe, and secured to the heel by means of screws.

A represents the metallic cap fitted to the face of the heel by means of screws I I, and surrounded by a flange B, projecting slightly over the sides of the heel. Within this flange, and upon the plate A, the elastic supplementary heel E is placed, and secured in position by means of a screw passing through its centre, as seen at F, fig. 2.

By this construction of the heel, the elastic plate E is kept securely in place by the flange B, and prevented from spreading out of shape when in use. When sufficiently worn, it can be easily removed and another plate substituted.

Having thus described my invention, what I claim as new, and desire to secure by Letters Patent, is—

The metallic plate A, having flanges B D, in combination with the heel E, and the central screw for attaching said heel to the plate, as herein shown and described.

GEORGE LANE.
